BUCKLE

Harry V. Anderson, Minneapolis, Minn., assignor of one-half to James M. Abeln, Hopkins, Minn.

Application June 12, 1957, Serial No. 665,225

1 Claim. (Cl. 24—197)

The invention herein has relation to a buckle of new and improved construction for detachably connecting end portions of straps, or the like, which can be employed for various purposes, as, for example, as part of a belt, suspenders, etc.

In the accompanying drawing forming a part of this specification:

Fig. 1 is a front elevational view of a buckle made according to the invention as when applied to use;

Fig. 2 is a transverse sectional view of the buckle, taken on line 2—2 in Fig. 1;

Fig. 3 is a front elevational view of one of a pair of fastener members of the buckle;

Fig. 4 is a front elevational view of the other fastener member of said buckle; and

Fig. 5 is a front perspective view of the fastener member of Fig. 3.

The buckle of this invention is for detachably connecting end portions, such as denoted at 10 and 11, of straps, or the like, and consists of a pair of fastener members, indicated 12 and 13, respectively, each of flat rigid material which desirably can be sheet metal.

The fastener member 12, is of general Z-shape in cross section transversely of the buckle, and when viewed crosswise thereof, is constituted as a body 14, a tongue 15 and a neck or strip 16 between and connecting said body and tongue.

The body 14 of the fastener member 12 is as disclosed of rectangular configuration. First and second spaced, parallel, longitudinal, rectangular slots through said body are represented 17 and 18, respectively. The rectangular slots 17 and 18 are bounded at their opposite ends by opposite end portions, each designated 19, of the body 14, said rectangular slot 17 is bounded at an exterior side thereof by a cross bar 20 and at an interior side thereof by a cross bar 21 of said body, and said rectangular slot 18 is bounded at its exterior side by said cross bar 21 and at its interior side by a cross bar 22 of the body. The rectangular slots 17 and 18 are of equal length and width, as are also the cross bars 20, 21 and 22. The exterior edge of the cross bar 20, together with the adjacent end edges of the opposite end portions 19, defines the exterior edge of the body 14, and the interior edge of the cross bar 22 defines the interior edge of said body.

The neck or strip 16 is rectangular and of uniform width. A rearward side edge of said neck or strip is integral with the interior edge of the cross bar 22 of the body 14 and the neck or strip extends forwardly from said body in substantially perpendicular relation thereto. As disclosed, the opposite ends of the neck or strip are in alignment transversely of the buckle with the interior edges of the opposite end portions, respectively, of the body 14, which interior edges also provide surfaces bounding the opposite ends of the rectangular slots 17 and 18.

The tongue 15 of the fastener member 12 also is of rectangular configuration and of uniform width. An exterior side edge of said tongue is integral with a forward side edge of the neck or strip 16 and the tongue extends inte-

2

riorly of the buckle in substantially perpendicular relation to said neck or strip and in parallel relation to the body 14. The opposite ends of said tongue are in alignment transversely of the buckle with the opposite ends, respectively, of the neck or strip 16, and the interior edge of the tongue is parallel with said neck or strip and the exterior edge of the body 14 of the fastener member 12.

As shown, the tongue 15 is of width somewhat less than is the body 14 of the fastener member 12, and the width of said tongue approaches a measurement representing three times the width of the neck or strip 16 of said fastener member. Each of the rectangular slots 17, 18 has a width equal to that of each of the cross bars 20, 21, 22, and said neck or strip is of width approximately the same as, or a bit greater than, that of each rectangular slot and cross bar.

The fastener member 13 is constituted as a body which as disclosed is substantially a duplicate of the body 14 of the fastener member 12. First and second spaced, parallel, longitudinal, rectangular slots through said fastener member or body 13 are indicated 23 and 24, respectively. The rectangular slots 23 and 24 are bounded at their opposite ends by opposite end portions, each represented 25, of the fastener member or body 13, said rectangular slot 23 is bounded at an exterior side thereof by a cross bar 26 and at an interior side thereof by cross bar 27 of said fastener member or body, and said rectangular slot 24 is bounded at its exterior side by said cross bar 27 and at its interior side by a cross bar 28 of the frame member or body. The rectangular slots 23 and 24 and the cross bars 26, 27 and 28 are of the same length and width as are the slots 17 and 18 and the cross bars 20, 21 and 22 of the body 14 of the fastener member 12. The exterior edge of the cross bar 26, together with the adjacent end edges of the opposite end portions 25, defines the exterior edge of the fastener member or body 13, and the interior edge of the cross bar 28, together with the adjacent end edges of said opposite end portions, defines the interior edge of said fastener member or body.

The strap end portion 10 extends interiorly over and in engaged relation with the forward surface of the cross bar 20, rearwardly through the rectangular slot 17, over and in engaged relation with the rearward surface of the cross bar 21, forwardly through the rectangular slot 18, over and in engaged relation with portions of the forward surface of the cross bar 22 and an exterior surface of the neck or strip 16, interiorly over and in engaged relation with the forward surface of the tongue 15, rearwardly over and in engaged relation with the interior edge of said tongue, exteriorly over and in engaged relation with the rearward surface of the tongue and over and in engaged relation with the rearward surface of said cross bar 22. As disclosed, the strap end portion 10 extends exteriorly from the location of the cross bar 22 over and in engaged relation with the rearward surface of the cross bar 20. It could, however, pass forwardly through the rectangular slot 17 and over and in engaged relation with the forward surface of the cross bar 20, at the rear of the part of said strap end portion shown as engaged with said forward surface of said cross bar.

The strap end portion 11 extends interiorly over and in engaged relation with the forward surface of the cross bar 26, rearwardly through the rectangular slot 23 and exteriorly over and in engaged relation with the rearward surface of said cross bar 26. A loop of said strap end portion thus provided is secured to the fastener member or body 13 by appropriate means such as stitching indicated at 29.

When the fastener members of the buckle are to be detachably connected as in Figs. 1 and 2 of the drawing, the tongue 15 and neck or strip 16 of the fastener member 12, with the strap end portion 10 applied thereto in

the manner as hereinbefore set forth, will be inserted forwardly through the rectangular slot 24 in the fastener member 13 and moved to a position therein situating the meeting edges of the body 14 and the neck or strip 16 and parts of the strap end portion 10 at the opposite sides of said meeting edges, in adjacent relation to the rearward surface of said fastener member 13. The fastener member 12 will then be rotated in said rectangular slot 24 to bring a part of the strap end portion 10 engaging the rearward surface of the tongue 15 into engaged relation with a part of the strap end portion 11 engaging the forward surface of the cross bar 26 of said strap end portion 11. When the fastener members are so relatively situated the neck or strip 16 and the parts of the strap end portion 10 thereon will be confined in the rectangular slot 24 in the fastener member 13 with said neck or strip in substantially perpendicular relation to said fastener member 13 and the fastener members themselves in adjacent substantially parallel relation.

Tension exerted upon the strap end portions 10 and 11 tending to move the fastener members 12 and 13 apart will maintain the part of the strap end portion 10 extending across the rear surface of the tongue 15 in engaged relation with the part of the strap end portion 11 extending across the front surface of the cross bar 28, the bodies of said fastener members in parallel, adjacent relation and the neck or strip 16 and the fastener member 13 in perpendicular relation with each other. The length of the strap end portion 10 is readily and easily adjustable in a manner which will be apparent, and pendant parts of

the strap end portions will be invisible at the rearward side of the buckle when it is in use.

What is claimed is:

- 5 A buckle of flat rigid material comprising a fastener member of general Z-shape constituted as a first flat body, a tongue, and a neck between and connecting said first body and tongue, the first body having spaced parallel first and second elongated slots therethrough bounded at their opposite ends by opposite end portions and defining spaced parallel first, second and third cross bars, said neck being integral with and extending from the first body in substantially perpendicular relation thereto, said tongue extending forwardly in substantially perpendicular relation to the neck and in parallel relation to said first body, the fastener member being adapted to receive a strap portion extending over said first cross bar, through the first elongated slot, under said second cross bar, through the second slot, and over said third cross bar, neck and tongue, and rearwardly under said tongue, neck and first body, and a second flat body having an elongated slot therethrough, bounded at its opposite ends by opposite end portions and at its opposite sides by cross bars, said elongated slot in said second body being adapted to receive the tongue and neck of the fastener member and parts of said strap portion thereon and said neck when so received being in perpendicular relation to said second body and confined in the last mentioned elongated slot.
